United States Patent Office.

E. QUINLAN, OF SHEBOYGAN FALLS, WISCONSIN.

Letters Patent No. 80,564, dated August 4, 1868.

IMPROVEMENT IN MACHINES FOR POLISHING WOODEN HANDLES.

The Schedule referred to in these Letters Patent and making part of the same.

TO ALL WHOM IT MAY CONCERN:

Be it known that I, E. QUINLAN, of Sheboygan Falls, in the county of Sheboygan, and State of Wisconsin, have invented a new and useful Improvement in Burnishing-Mandrels; and I do hereby declare the following to be a full, clear, and exact description of the same, reference being had to the accompanying drawings, in which—

Figure 1 is a front elevation of my mandrel.

Figure 2 is a side elevation of the same.

Figure 3 is a vertical longitudinal section of the same.

My invention relates to a machine for finishing the surface of straight, or nearly straight, turned work, such as rake-handles, fork-handles, broom-handles, &c., and it consists in a hollow mandrel, having steel or other burnishers attached, and so located that, as the work passes through the mandrel, the burnishers will press upon its surface and reduce the same to a fine smoothness, highly desirable, and not to be attained in any other way.

That others may understand the construction of my apparatus, I will fully describe it.

A is a hollow mandrel, set in head-blocks B, and rotated with great rapidity by some convenient means, as by a belt to a pulley upon a revolving shaft, if used in a shop where power is employed. The mandrel A has at one end a bell-mouth, as shown in figs. 1 and 3, to facilitate the entering of the work. Immediately behind the head in which is the bell-mouth, a portion of the mandrel is cut away on each of two opposite sides, sufficient to expose the hollow in the mandrel, and from each of the remaining opposite sides, between the orifices above referred to, are projected short arms or studs C C, to the outer ends of which are attached the springs D D, which I prefer to employ to produce the requisite frictional pressure upon the burnishers. The burnishers may be of steel, and form parts of the springs D, or they may be made of any of the well-known substances suitable for that purpose, and attached to the springs by some convenient means.

I am aware that hollow mandrels have been employed to hold cutters for the production of cylindrical forms, as in turning rake-handles, &c., and I therefore do not claim anything as to the hollow mandrel alone, but only in connection with burnishers to finish the surfaces as left by the cutters, and I do not wish to be understood as confining myself to the particular details of construction shown, because the construction may be varied, especially to adapt the apparatus to one particular line of work, and so long as a revolving motion should be applied to polish by friction, or burnishing of turned work of the character mentioned, I should consider it as substantially my invention.

Having described my invention, what I claim as new, is—

A hollow mandrel, A, with the burnishers D D attached thereto, substantially as and for the purpose set forth.
